(57) **CLAIM**

The ornamental design for a portion for electronic cigarette as shown and described.

DESCRIPTION

FIG. 1.1 is a perspective view of a portion for electronic cigarette, showing our new design;

FIG. 1.2 is a front view thereof;

FIG. 1.3 is a rear view thereof;

FIG. 1.4 is a left side view thereof;

FIG. 1.5 is a right side view thereof;

FIG. 1.6 is a top view thereof; and

FIG. 1.7 is a bottom view thereof.

The broken lines in FIG. 1.7 depict portions of the part for electronic cigarette that form no part of the claimed design.

1 Claim, 7 Drawing Sheets
